FREQUENCY MODULATION RECEIVER

Roy A. Weagant, Douglaston, N. Y., assignor to
Radio Corporation of America, a corporation
of Delaware

Application May 26, 1942, Serial No. 444,506

4 Claims. (CL 250—20)

My present invention relates generally to a method of, and means for, minimizing amplitude modulation effects in receivers of angular velocity-modulated carrier waves, and more particularly to a receiver of frequency modulated carrier waves embodying a novel and simplified form of amplitude modulation elimination means.

One of the main objects of my invention is to provide a receiver of angular velocity-modulated carrier waves which embodies a carrier wave degenerative circuit prior to the demodulator network; the degenerative circuit functioning to insure a substantially flat-top response curve at the network feeding the demodulator.

Another important object of my invention is to provide in combination with a demodulator of angular velocity-modulated carrier waves a stage of amplification of such waves; the amplification stage including a degenerative circuit arrangement which insures a substantially flat-top response curve thereby preventing amplitude modulation effects from arising in the waves applied to the demodulator.

Another object of this invention is to provide a novel method of receiving frequency modulated carrier waves (FM) without the use of an amplitude modulation limiter per se; and at least one amplifier prior to the receiver demodulator embodying a simple circuit device for minimizing amplitude modulation effects.

Still other objects of the invention are to improve generally the simplicity and efficiency of FM receivers, and more especially to provide an FM receiver substantially free of amplitude modulation effects which commonly arise in such receivers.

The novel features which I believe to be characteristic of my invention are set forth with particularity in the appended claims; the invention itself, however, as to both its organization and method of operation will best be understood by reference to the following description taken in connection with the drawing in which I have indicated diagrammatically a circuit organization whereby my invention may be carried into effect.

In the drawing:

Fig. 1 schematically shows a receiver embodying the method of the invention.

Fig. 2a illustrates the ideal response curve of the radio frequency amplifier network.

Fig. 2b graphically illustrates two types of uncorrected intermediate frequency (I. F.) pass band curves commonly encountered in FM receivers.

Fig. 2c shows the effect of using the present invention.

Fig. 3 illustrates one embodiment of the invention.

Fig. 4 illustrates a modified form of the invention.

Referring now to the accompanying drawing, wherein like reference characters in the different figures designate similar circuit elements, the schematic networks of an FM receiver as shown in Fig. 1 generally comprise a signal collector 1 which feeds one or more stages of radio frequency amplification 2. The collector 1 may be of any desired type, a dipole being shown merely by way of example. The assigned FM (frequency modulation) broadcast band covers a range of 42 to 50 megacycles (mc), and each FM channel has a width of 200 kilocycles (kc.). At the FM transmitter the station carrier is actually deviated to a maximum deviation of approximately 75 kc. to each side of the mid-band, or center, frequency. As is well known in the art of FM transmission the station carrier is deviated in frequency in accordance with the amplitude of the modulation signal frequencies, the rate of deviation being dependent on the modulation frequencies per se. The carrier is radiated from the transmitter at a constant amplitude. Ideally, at the FM receiver it is desired to amplify the FM waves without the introduction of any amplitude modulation effects. This is obviously necessary because it is the function of the FM demodulator to derive the modulation signals from the amplified FM waves. The introduction of amplitude modulation components in the FM waves applied to the detector results in harmonic distortion.

The amplifier 2 is given a wide pass band, such as is illustrated in Fig. 2a. From that figure it will be seen that the pass band is substantially wider than the overall carrier deviation whose extremities are spaced some 150 kc. apart. The radio frequency amplifier 2 will include one or more tunable selector circuits which are, of course, adjusted to the center frequency of the desired FM channel. By giving the radio frequency amplifier a wide flat-top response characteristic, and whose width is substantially wider than the overall frequency deviation range of the received FM waves, amplitude modulation effects due to the selector circuits prior to the first detector 3 will not appear.

The local oscillator 4 is tuned through a frequency range such as to produce local oscillations which, when applied to the converter stage 3.

produces the I. F. energy in the output circuit of the latter. The I. F. energy covers the same frequency deviation range as the radio frequency energy, but the center frequency has been reduced to the operating I. F. value. The latter may be chosen from a range of 2 to 18 megacycles (mc.), such as, for example, 4.3 mc.

The I. F. amplifier 5 may comprise one or more stages of I. F. amplification. Each I. F. amplifier comprises, of course, a tube having a band pass input circuit and a band pass output circuit. The FM detector 6 has a discriminator input network 7 which may be of the type disclosed and claimed by S. W. Seeley in his U. S. Patent 2,121,103, granted June 21, 1938. Of course, any other type of FM detector circuit may be employed. The audio frequency output of the detector may be amplified in one or more stages of audio frequency amplification, and a reproducer will follow the audio frequency amplifier network.

From a generic viewpoint I utilize degenerative carrier feedback in producing the novel method of my invention. The numeral 8 in Fig. 1 denotes the degenerative feedback path, and it is to be understood that the I. F. energy may be degeneratively fed back from the I. F. amplifier output to its input in any predetermined amount which will produce the desirable results of this invention. Of course, the degenerative FM energy feedback may be provided between the output and input of each of the I. F. amplifiers, or single stage feedback may be combined with overall I. F. amplifier feedback. Also, degenerative feedback may be employed in the radio frequency stages.

To appreciate fully the utility and advantages of the present method, attention is directed to Fig. 2b which shows the usual type of uncorrected I. F. pass band encountered in FM receivers of present day construction. The curve A has a round top, while the curve B has a central depression with spaced peaks. Either of these response curves in the I. F. networks will cause amplitude modulation effects to appear in the FM energy impressed upon the discriminator input network of the demodulator. The response curves of the types of A and B arise by virtue of many causes. In the first place, it is difficult to manufacture an I. F. transformer having coupled primary and secondary circuits whose pass band will have a flat top. In the second place, even if it were theoretically possible to make the response curve of the I. F. amplifier flat enough, as a practical matter the I. F. amplifier components are not stable enough to insure that the amplifier would remain aligned with this characteristic. Temperature, humidity, vibration and ageing effects cause even the best of present day receivers to drift out of line.

In the past various arrangements have been proposed for minimizing amplitude modulation effects introduced by virtue of the failure to provide a flat-top response curve in the I. F. amplifier feeding the detector. A limiter stage has been inserted immediately prior to the demodulator. However, a limiter stage requires that the signal input level be relatively high. Furthermore, it has been proposed to design the resonant circuits of the I. F. amplifier in the form of complex filter circuits. However, such a solution is uneconomical by virtue of the number of circuit components required. According to my present invention sufficient I. F. degeneration is introduced in the I. F. amplifier network so as to provide an I. F. response curve as shown in Fig. 2c.

It will be noted that amplitude modulation effects introduced by either of curves A or B of Fig. 2b are virtually eliminated by virtue of the flat-top response curve of Fig. 2c.

In Fig. 3 there is shown a desirable method of introducing I. F. degeneration in the I. F. amplifier immediately preceding the detector. It will be understood that the transformer 9 is an I. F. transformer whose primary and secondary circuits are each fixedly tuned to the center frequency of the applied FM waves, in this case the operating I. F. value. The pass band of the transformer 9 is substantially 150 kc. wide, and the response curve thereof is made as close to a flat top as is economical to secure with the usual manufacturing methods. The amplifier tube 10 has its cathode magnetically coupled, as at 11, to the resonant output circuit 12. The cathode coil 13 may be arranged in series with the usual carrier-bypassed grid biasing resistor 14.

The resonant output circuit 12 is reactively coupled to the resonant input circuit 15 of the FM detector. Here, again, as pointed out above, the detector is of the well known type disclosed in the aforesaid Seeley patent. It is not believed necessary to describe the operation of the detector. Its functioning is clearly described in the Seeley patent, and it is well known at this date to those skilled in the art of constructing FM receivers. Sufficient degenerative feedback is had to the grid-cathode circuit of I. F. amplifier 10 to convert the undesirable response curves of Fig. 2b to the highly desirable flat-top response curves of Fig. 2c. There is fed back to the grid circuit of amplifier 10 FM wave voltage developed across circuit 12, and the feedback of the voltage is in a degenerative phase. Hence, it will be seen that no additional stage of limiting is required in my present method. It is but necessary to provide in the cathode lead of the I. F. amplifier 10 a coil 13. The complete simplicity of the present invention, as contrasted to the relatively complex devices previously used to compensate for modulation effects, will be obvious to those skilled in the art. Of course, the I. F. stage prior to the amplifier 10 may also embody a degenerative feedback coil in its cathode lead.

In Fig. 4 there is shown a modified form of a degenerative circuit. In this case the I. F. amplifier tube 10 has its cathode connected to ground through a path comprising the carrier-bypassed biasing resistor 14, adjustable tap 20, and the portion of coil 21 between tap 20 and ground. The coil 21 is connected in shunt with a condenser 22. The circuit 21-22 is tuned to the operating I. F. value, and, hence, it will develop thereacross FM voltage. Adjustment of tap 20 to a proper point on coil 21 will provide the desired amount of degenerative feedback. If desired, automatic volume control bias (AVC) may be applied to the signal grid of amplifier 10. It is not believed necessary to show any particular mode of securing the AVC bias, since those skilled in the art are fully aware of the manner of deriving such bias.

One of the advantages of utilizing degenerative FM voltage feedback in one or more I. F. amplifier stages is the fact that such factors as temperature, humidity, vibration and ageing effects do not appreciably affect a degenerative amplifier stage. Hence, the flat-top resonance curve will be maintained in spite of the usual effects which normally cause the I. F. amplifier to drift out of alignment with the desired char-

acteristic. It is, also, pointed out that the balanced detector which is employed reduces amplitude modulation to a degree which is sufficient for many purposes. The balance in the FM demodulator network rejects noise during no-signal periods but allows the noise to rise as the depth of modulation rises. Since the modulation rises with the noise, the effect is not as annoying as though it were continuously present. By utilizing the present invention to insure a flat-top response curve in the I. F. network feeding the detector the action of the balanced FM demodulator is enhanced. It is, also, of interest to note that, as employed under the present FM broadcasting channel assignments, the signal to noise ratio at the collector of the usual FM receiver is relatively high so that external noises are not an appreciable factor in the production of amplitude modulation.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a receiver of angular velocity-modulated carrier waves of the type comprising a demodulator of such waves preceded by an amplifier which is tuned to the mid-band frequency of the waves and has a normal pass band at least as wide as the overall frequency deviation range but which band has a shape such that amplitude modulation of said waves is produced; the improvement which comprises means for providing sufficient degenerative feedback of modulated carrier wave voltage between the output and input circuits of said amplifier to insure a substantially flat top response curve for said amplifier over said pass band thereby to eliminate said amplitude modulation.

2. In combination, in a frequency modulated carrier wave receiver, a frequency modulation detector, an amplifier having a resonant input circuit and a resonant output circuit, means coupling said resonant output circuit to said

detector, said amplifier having a pass band at least as wide as the over-all frequency deviation range of the amplified waves but whose response is such that amplitude modulation of the received waves occurs, and means providing sufficient degenerative feedback of the amplified modulated carrier wave energy between said resonant output circuit and said input circuit thereby to provide a substantially flat-top response curve over said pass band whereby said amplitude modulation is substantially reduced.

3. In a frequency modulation receiver of the superheterodyne type which includes at least one intermediate frequency amplifier having a non-uniform response curve such that amplitude modulation of received waves arises prior to a frequency modulation detector of the balanced type adapted to reject noise solely during no-signal periods; the improvement which comprises means providing sufficient degenerative feedback of frequency modulated carrier wave voltage between the output and input circuits of said amplifier thereby to insure a substantially flat-top response curve for said amplifier whereby the noise rejection action of the balanced detector is enhanced.

4. In combination, in a frequency modulated carrier wave receiver, a frequency modulation detector of the balanced type which has a noise rejection characteristic during no-signal periods but which allows noise to rise as the depth of modulation rises, an amplifier having a resonant input circuit and a resonant output circuit, means coupling said resonant output circuit to said detector, said amplifier having a pass band at least as wide as the over-all frequency deviation range of the amplified waves but whose shape is such as to give rise to amplitude modulation of the waves, and means in the space current path of the amplifier providing sufficient degenerative feedback of the amplified modulated carrier wave energy between said resonant output circuit and said input circuit to provide a substantially flat-top response curve over said pass band whereby said noise rejection characteristic is augmented during signal periods.

ROY A. WEAGANT.
